UNITED STATES PATENT OFFICE.

JULIUS GRUNER, OF TOWER, MINNESOTA.

CALCULATING OR COMPUTING MACHINE.

No. 888,525.

Specification of Letters Patent.

Patented June 19, 1906.

Application filed June 24, 1905. Serial No. 266,842.

To all whom it may concern:

Be it known that I, JULIUS GRUNER, a citizen of the United States, residing at Tower, in the county of St. Louis and State of Minnesota, have invented certain new and useful Improvements in Calculating or Computing Machines, of which the following is a specification.

This invention consists of a calculating or computing machine designed particularly for use by bookkeepers, timekeepers, or persons engaged in similar occupations or work involving calculations necessitating computation or figuring out of amounts due individuals in lieu of services performed or to secure similar results whether used for the above-mentioned purpose or for any other of various purposes to which a device of the character comprised in this invention may be put.

In its preferred adaptation the invention embodies a machine designed particularly for facilitating the posting of wages due employees of large concerns where the number of the employees is so large as to require a great amount of time and labor if the amount due each person is separately figured out by methods commonly used.

For a full description of the invention and the merits thereof and also to acquire a knowledge of the details of construction of the means for effecting the result reference is to be had to the following description and accompanying drawings, in which—

Figure 1 is a front elevation of a machine embodying the essential features of this invention. Fig. 2 is a vertical transverse sectional view. Fig. 3 is a horizontal sectional view taken about on the line X-X of Fig. 2. Fig. 4 is a horizontal sectional view taken about on the line Y-Y of Fig. 2. Fig. 5 is a plan view of a stopping-disk of modified form.

Corresponding and like parts are referred to in the following description and indicated in all the views of the drawings by the same reference characters.

The machine herein specifically described is used for calculating the wages of a large number of persons and is designed to enable one to quickly obtain the amount due persons working under different scales of wages and according to the number of days, or other units of time, dependent, of course, upon the

system which may be used in a particular concern by which such persons may be employed.

The machine consists of a suitable casing 1, and this casing is carried by a base 2 and may be of any ornamental configuration or otherwise, as desired, this being immaterial.

It is preferred that the rear of the casing 1 be

provided with a suitable door by which access may be had to the interior mechanisms arranged therein, which constitute the essential feature of the invention. Mounted in the casing 1 is a motor-shaft 3, said shaft being preferably arranged about central of the casing, being operated by means of a spring-motor 4, similar to those employed in clock-movements at present in use. The shaft 3

has its lower end mounted in a suitable bearing 5 upon the base 2 of the casing 1, and said shaft passes through a horizontal partition 6, just above the spring-motor 4, and then

through a second horizontal partition 7, some distance above the partition 6. A gear 8 is attached to the upper extremity of the shaft 3, and said gear is in mesh with sets of gear-wheels 9 and 10, arranged in pairs within the casing 1 and having suitable bearings upon the partition 7.

The gear-wheels 9 and 10 support sets of rollers 9^a and 10^a, one of said rollers being supported by each gear-wheel.

A pair of rollers constitute each set of rollers 9 and 10, and said sets of rollers are arranged side by side in the casing 1, endless belts or strips 11 and 12 connecting the pairs of rollers 9^a and 10^a, respectively. The strips or belts 11 and 12 may be made of suitable material, and it is preferred that the rollers about which they travel be provided with

small fine points 13 at intervals in the length thereof to prevent the strips or belts above mentioned from slipping. The belts 11 and 12 are provided upon the outer sides thereof with suitable indicating data, which will be described more clearly hereinafter, and the casing 1 is provided in the front thereof with sight-openings 14, which may be covered by glass or any transparent material,

if desired, through which certain of the indicating characters upon the belts 11 and 12 are discernible. The pairs or sets of rollers 9^a and 10^a constitute a movable computing or calculating device, and the motor 4

normally tends to actuate the shaft 3 to produce rotation of the various rollers 9^a and 10^a,

and thereby actuate the calculating or indicating mechanism just above described. The shaft 3, however, is normally prevented from rotation by means of a stopping mechanism consisting of a stopping-disk 15, said disk being arranged in the space between the partitions 6 and 7 of the casing 1 and rigidly secured to the shaft 3 for rotation therewith. The stopping-disk 15 is arranged horizontally 5 between the partitions 6 and 7, and projecting from the underside of said disk are a plurality of projections or pins 16. The various pins 16 are so arranged as to travel in concentrically-spaced paths of movement, so that a part extended into the path of movement of one of the projections 16 would not interfere or engage with any of the other pins or projections. Fig. 3 illustrates one arrangement of the projections 16, and Fig. 5 a second arrangement of 10 said projections, these figures illustrating that various arrangements may be utilized in the practical embodiment of the invention.

The operation of the stopping-disk 15 is governed by a number of key-bars, (indicated at 17 and 17^a), the key-bars 17 being arranged upon one side of a line vertically central of the machine, whereas the key-bars 17^a are arranged upon the opposite side of such a line. The key-bars aforesaid are provided in 15 a number corresponding with the number of projections or pins 16, each key-bar being adapted to coöperate with a single one of said projections, so as to stop the stopping-disk at a predetermined point in the movement thereof when a key-bar is actuated. The key-bars 17 and 17^a consist of levers, which are pivoted to a pivot-rod 18, mounted in the casing 1 and preferably supported upon the partition 6. The bars 17 and 17^a are pivoted 20 between the ends thereof, the inner extremities of said key-bars being formed with projections, those carried by the key-bars 17 being indicated at 19 and those carried by the key-bars 17^a being indicated at 19^a; said projections 19 and 19^a extending upwardly 25 from the key-bars, so that they may be disposed in the path of movement of a certain one of the projections 16, carried by the stopping-disk 15. A finger-piece 20 is provided 30 for each of the key-bars 17 and 17^a, being carried at the outer extremity thereof. Projecting downwardly from each key-bar near the outer extremity and exterior of the casing 1 is a hook 21, and the various hooks 21 of the key-bars are adapted to coöperate or engage with a detent-bar 22, pivoted at 23 to the outer side of the casing 1 at the front thereof. The detent-bar 22 extends transversely of the casing 1 and is adapted to co- 35 operate with the hooks 21 on any one of the key-bars upon actuation of the latter when forced downwardly. A spring 24, interposed between the detent-bar 22 and the casing 1, normally tends to force said detent-bar out-

wardly, and a plurality of springs 25 are interposed between the respective key-bars 17 and 17^a and the partition 6, being arranged in the casing 1, said springs normally exerting an upward pressure to hold the key-bars at the limit of the upward movement thereof. 40

A description of the operation of the machine illustrated in the drawings will show the advantages thereof. The machine carries at its upper portion or in any place preferably a sign 26, which indicates that the same is for calculating on the basis of "twenty-six days to a month," a common method of computing wages or salaries of employees. The indicating data upon the belts or strips 11 and 12, which pass about the rollers 9^a and 10^a, respectively, preferably consist of twenty vertical spaces, each indicated at A. At the upper end of each space is a designation which states the amount of salary of an employee per month. For instance, these designations may be "\$16," "\$40," "\$50," "\$65," &c. The portions of the spaces A below the uppermost of the designations indicative of salary per month are divided into two columns, one for "dollars" and one for "cents." 45 As shown in Figs. 1 and 4, at the left-hand side of each sight-opening 14 is an indicating plate or strip 27, carrying a column of figures which are denoted at the upper end of the column as indicative of a certain number of days. The figures on the right-hand plate 27 run from one to thirty and include one-half and one-fourth day designations, whereas the figures on the left-hand plate 27 (see Fig. 1) run from thirty-one up to one hundred, preferably. The spaces A in the length of the strips or belts 11 and 12 are subdivided into divisions transversely, each division giving the amount in actual figures, dependent, of course, upon the amount of salary indicated at the top of the space A for a single day's work or a number of days' work. Thus under the scale of twenty-six days to the month a man getting wages of thirty-two dollars a month will get one dollar and twenty-three cents for one day's work and nine dollars and eighty-five cents for eight days' work. When the rollers or belts 11 and 12 are actuated, a vertical space A will always be revealed at each sight-opening 14; 50 when a key-bar is actuated to stop the machine, and thus the operator will have before him a scale which will immediately indicate the wages due for a predetermined time. When twenty spaces A are provided for each belt 11 and 12, it is designed that the machine may be stopped with any of the spaces A at sight-openings 14, and therefore the projections 16 are twenty in number and the key-bars 17 and 17^a are likewise twenty in number. The finger-piece 20 of each key-bar has a character or designation thereon corresponding, preferably, with the character or designation 55

at the head or top of each space A. Thus when the operator of the machine desires to know the wages due a person getting a salary of thirty-two dollars a month for ninety-five days according to the scale of wages at twenty-six days to the month, and the space A having the designation fifty dollars at the top thereof being in front of the sight-openings 14, the operator will depress the key-bar having the numeral 32 upon its finger-piece. When this key-bar is forced downwardly, the hook 21 thereof rides against the upper portion of the detent-bar 22, which detent-bar has been in engagement with the key-bar 17^a, (designated at the numeral 50.) As soon as the hook 21 of the key-bar (designated by the numeral 32) forces the detent-bar 22 back as it engages the same said detent-bar is simultaneously disengaged from the hook 21 of the key-bar, (designated by the numeral 50,) permitting the last-mentioned key-bar to move upwardly at its outer end, so that the projection 19^a of this key-bar is disengaged from the pin or projection 16, by which the stepping-disk 15 has previously been held from movement. The stepping-disk, as soon as the projection 19^a above mentioned is disengaged therefrom, immediately begins to turn under the actuation of the motor-spring 4; but the key-bar having the designation 32 has now been engaged with the detent-bar, and the projection 19 which extends from this key-bar is in the path of movement of one of the projections 16 upon the stepping-disk 15. As soon as the projection 16 of the stepping-disk 15 strikes the projection 19 of the key-bar, (indicated by the numeral 32,) said stepping-disk is stopped from rotation, and the positions of the spaces A of the strips 11 and 12 being arranged particularly with reference to the key-bars, the spaces A having the salary-marks "32" at its head will appear before the sight-openings 14. Vertical guide-rods 28 at the right of each sight-opening 14 carry slide-frames 29, each frame being of a size sufficient to inclose one of the day designations upon the plates 27 and one of the salary designations in the length of the columns of the spaces A, and the operator as soon as the machine stops upon depression of the key-bar designated 32 may readily grasp one of the slide-frames 29 until the same is moved to the numeral "95" in the length of the plate 27 at the left in Fig. 1, and he will immediately see that for ninety-five days' work at wages amounting to thirty-two dollars a month the person is entitled to one hundred and sixteen dollars and ninety-two cents.

It will be obvious that various other designations may be used as far as indicated matter carried by the plates 27 and strips 11 and 12 is concerned, so as to adapt the machine embodying the invention to uses in various

businesses. However, such uses will not be described, as the mechanism may be employed in so many different ways to accomplish the results so far as the principle of operation of the machine is involved.

The belt or strip 11 rotates in one direction, whereas the belt or strip 12 rotates in the opposite direction, due to the arrangement of the gear-wheel 8, and the gear-wheels 9 and 10 preferably make two revolutions to one revolution of the wheel 8, and in the construction illustrated such two revolutions will turn the belts or strips 11 and 12 just once with reference to the sight-openings 14. It will be understood that the number of the rollers 9^a and 10^a may be increased or decreased within the contemplation of the invention and as required by various modifications thereof. The projections 19 of the key-bars 17 are concaved, preferably, upon one side, so as to permit engagement of the pins as the disk 15 rotates, the projections 19 being concaved on the opposite sides.

The advantages of the invention from a practical standpoint are obvious, as it will be seen that the operator of the machine can readily determine or secure the necessary calculation desired by him very quickly, thereby increasing the amount of work which he may perform in an ascertained time to an extent which is of great importance for obvious reasons.

Having thus described the invention, what is claimed as new is—

1. In a computing and calculating machine, the combination of a movable computing device, a rotatable stopping-disk operatively connected therewith, projections extended from the stopping-disk at different distances from the line of axis thereof, a plurality of key-bars, and members projected from the key-bars to coact with a single projection on the stopping-disk at a predetermined point in the movement of said disk.

2. A device of the character described comprising a casing, a computing device within the casing and comprising sets of rollers and belts containing suitable indicia and mounted around said rollers, a revoluble disk connected with said rollers to move therewith and provided with a series of projections at different distances from the center of rotation of said disk, a series of key-bars arranged parallel in said casing and each of which is designed for contact with one of the projections on said disk, and a detent-bar mounted for engagement with said key-bars, as and for the purpose set forth.

3. A device of the character described comprising a casing, rollers mounted in said casing and containing piercing projections, and belts containing suitable indicia and traveling around said rollers in engagement with said projections, a revoluble disk connected

- with said rollers to move therewith and provided with a series of projections at different distances from the center of rotation of said disk, a series of key-bars arranged parallel in 5 said casing and each of which is designed for contact with one of the projections on said disk, and a detent-bar mounted for engagement with said key-bars, as and for the purpose set forth.
- 10 4. A device of the character described comprising a casing, a computing device within said casing, a revoluble disk operatively connected with said computing device to move therewith, means for moving said disk and 15 computing device, and provided with a series of projections, a series of key-bars mounted in said casing and extending through the front side of the same and arranged parallel, each one of said key-bars being provided with 20 a downwardly-extending hook, and a detent-bar 22 pivotally mounted along the front side of the casing and spring-pressed toward the hooks of said key-bars, as and for the purpose set forth.

5. A device of the character described comprising a casing, a computing device within the casing and comprising sets of rollers and belts containing suitable indicia and mounted around said rollers, a revoluble disk connected with said rollers to move therewith 25 and provided with a series of projections at different distances from the center of rotation of said disk, a series of key-bars arranged parallel in said casing and each of which is designed for contact with one of the projections in said disk, a detent-bar mounted for engagement with said key-bars, a vertical 30 guide-rod secured on said casing, and a slide-frame designed to be brought in front of the indicia or other characters carried by said 35 belts.

In testimony whereof I affix my signature in presence of two witnesses.

JULIUS GRUNER. [L. S.]
